Des. 224,102

Patented July 4, 1972

224,102

AUTOMATIC PIPETTE

Earl F. Raczak, Southampton, Pa., assignor to
Bio/Data Corporation, Hatboro, Pa.

Filed Jan. 28, 1970, Ser. No. 21,222

Term of patent 14 years

Int. Cl. D24—02

U.S. Cl. D16—2

FIG. 1

FIG. 2

FIG. 3

FIG. 4

FIG. 5

FIG. 1 is a front three-quarter view of an automatic pipette showing my new design.

FIG. 2 is a side elevational view;

FIG. 3 is a rear elevational view;

FIG. 4 is a top plan view; and

FIG. 5 is a bottom plan view.

I claim:

The ornamental design for an automatic pipette, substantially as shown.
